FRICTION LIGHTER

Josef Edenburg, Vienna, Germany; vested in the
Alien Property CustodianApplication April 10, 1940, Serial No. 328,885
In Germany April 24, 1939

5 Claims. (Cl. 67—7.1)

This invention relates to friction lighters and is particularly directed to a lighter capable of combination with other useful articles, and which may be easily and safely manipulated with one hand.

It has already been known to construct lighters capable of combination with other suitable articles, such as fountain-pens, lead pencils and the like, and to provide these lighters with actuating means terminating in a yieldable portion devised after the manner of the well known pocket clip. In these known devices the construction is of such a kind that pressure exercised upon the yieldable actuating means disengages a catch from a notch on the extinguishing cap and thus opens the cap of the lighter, while for the closing of the cap a second pressing action is necessary which must be exerted upon the heated cap. It is obvious, therefore, that in using one of the known devices the manipulator of the lighter runs the risk of burning his finger.

Hence, the object of the present invention is the provision of a lighter, capable of combination with a fountain-pen or the like, which overcomes the aforesaid drawback. In other words, what I want to produce is a completely automatic lighter of this type which may be manipulated with ease and safety with one hand and without the slightest risk for the manipulator of the device to burn his finger.

To solve this problem I provide the cylindrical staff-like lighter body with rod-like longitudinally shiftable actuating means being at one end pivotally connected to the extinguishing cap which also serves as driver for the friction wheel by placing these shiftable actuating means under the control of a tension spring which at the end of each actuation automatically returns the shiftable actuating means to their starting position.

In order to make my invention more readily understood I will now proceed to describe it with the aid of the accompanying drawing which forms a part of this specification and in which the same or corresponding numerals of reference indicate the same or corresponding parts. However, it is to be understood that changes, variations and modifications which come within the scope of the claims hereunto appended can be resorted to.

In the drawing—

Fig. 1 is a side view of the invention on an enlarged scale, partly in section;

Fig. 2 is likewise a side view of the invention

showing the hollow extension of the staff-like lighter-body provided with an internally threaded opening;

Fig. 3 is a side view of a fountain-pen provided at both ends with externally threaded portions for fastening it in the hollow extension of the lighter;

Fig. 4 is a view of a lead pencil provided with a threaded portion for fastening it in the hollow extension of the lighter;

Fig. 5 is a view of the interiorly threaded auxiliary member by means of which the lighter, fountain-pen and lead pencil may be assembled to form one single unit.

15 In the drawing 1 is the fuel chamber of the pocket-lighter shaped like a cylindrical staff and having the thickness of the customary fountain-pen. Mounted on the upper wall 2 of the staff is a bearing 3 in which is rotatably journaled by means of a shaft 6 a friction or abrading wheel 4 as well as an extinguishing cap 5, which latter in order to conform to the diameter of the staff is naturally of comparatively small size. The extinguishing cap 5 acts in known manner 20 by means of a plate spring 7 upon the claw-shaped side face of the abrading wheel, so that whenever the cap is opened the abrading wheel is rotated causing the latter to draw sparks from the spark producing member 8 whereby the fuel saturated wick 9 will become inflamed. Because 25 of its small size the extinguishing cap 5 will not be actuated directly but by means of the element 10 which is shiftably mounted on the staff 1 by means of a loop 11 and which at its upper 30 end 12 is pivotally connected to the end of the extinguishing cap by means of a bolt 13. Attached to the element 10 is a tension spring 14 which automatically forces the element 10 back into its starting position after each actuation of 35 the extinguishing cap. Spring 14 is arranged in a longitudinal recess 15 of the shaft 1 and suitably fastened to the upper wall 2 of the staff. The longitudinal opening of the recess 15 in the staff 1 is covered up by the element 10, for 40 which reason the spring 14 is completely enclosed in the recess, the latter serving as housing for the spring. For its convenient manipulation the element 10 is provided with a projection 16 which in the drawing is shown with a fluted surface 45 to further facilitate the operation of the device. The lower portion 17 of the shiftable element 10 is constructed after the manner of the well-known pocket clip for securing the lighter to the pocket of its owner.

As heretofore described the device is a com-

pletely automatic lighter which upon actuation of the element 10 becomes lighted and which upon release of the pressure upon element 10 automatically closes because of the spring action of spring 14. However, it is also possible to change the device to a semi-automatic one by providing staff 1 with a recess 19 serving as catch for the ball 18 at the end of the clip 17 when the latter is in its lowermost position, whereupon the lighter will remain inflamed until a pressure upon ball 18 disengages the ball from its position in catch 19 and thus enables spring 14 to close the cap.

The lighter body 1 is provided with a hollow extension 20 whose open end 21 is internally threaded to receive the externally threaded end 24 of a short-sized fountain-pen 22 or the threaded end 24' of a lead pencil 23, completing in this way either the fountain-pen or the lead pencil to the customary size. It is further contemplated to provide the fountain-pen 22 with a second exteriorly threaded portion 25, making it possible in this way to screw the threaded end 25 with pen 26 projecting from it into the hollow extension 20, the latter serving in this case as a protective housing for the pen.

The invention further provides a hollow sleeve-like auxiliary member 27 which is internally threaded and by means of which the lighter, fountain-pen and pencil may be assembled to form one single unit. For this purpose the fountain-pen 22 is screwed into the hollow extension 20, after which the threaded portion 25 of the fountain-pen is fastened in one end of the auxiliary member 27 while the lead pencil 23 is 35 screwed into the other end of it.

What I claim is:

1. The combination of a friction lighter and a writing implement, comprising a staff-like writing implement and lighter body having a fuel chamber therein, an actuating member comprising manual operating means, said actuating member being shiftably mounted longitudinally of and on the outside of said lighter body, said lighter body having a longitudinal recess thereon, a tension spring mounted in said recess, said recess and tension spring being covered and concealed by said actuating member, said tension spring adapted to return said actuating member to its starting position at the end of each actuation, an extinguishing cap pivotally mounted on said lighter body and pivotally connected to said actuating member to be actuated thereby and to be returned by said tension spring, an abrading element rotatably mounted on said lighter body and in driving engagement with said extinguishing cap to be driven thereby, a spark producing member supported on said lighter body to be acted upon by said abrading element, and a wick supplied with fuel from said fuel chamber and arranged on said lighter body within range of the sparks of said spark producing element and adapted to be extinguished by said extinguishing cap.

2. In a friction lighter capable of combination with a lead pencil, a fountain-pen and the like, a staff-like lighter body having a fuel chamber therein, an actuating member comprising manual operating means and provided at its lower end with a yieldable extension, said actuating member being shiftably mounted longitudinally on the outside of said lighter body, said lighter body having a longitudinal recess thereon, a tension spring mounted in said recess, said recess and tension spring being covered and concealed by

said actuating member, said tension spring adapted to return said actuating member to its starting position on the end of each actuation, an extinguishing cap pivotally mounted on said lighter body and pivotally connected to said actuating member to be actuated thereby and to be returned by said tension spring, an abrading element rotatably mounted on said lighter body and in driving engagement with said extinguishing cap to be driven thereby, a spark producing member suitably supported on said lighter body to be acted upon by said abrading element, and a wick supplied with fuel from said fuel chamber within range of the sparks of said spark producing element and adapted to be extinguished by said extinguishing cap.

3. In a friction lighter capable of combination with a lead pencil, fountain-pen and the like, a staff-like lighter body having a fuel chamber therein, an actuating member comprising manual operating means and provided at its lower end with a yieldable extension, said actuating member being shiftably mounted longitudinally of and on the outside of said lighter body, said lighter body having a longitudinal recess thereon, a tension spring mounted in said recess, said recess and tension spring being covered and concealed by said actuating member, said tension spring adapted to return said actuating member to its starting position on the end of each actuation, an extinguishing cap pivotally mounted on said lighter body and pivotally connected to said actuating member to be actuated thereby and to be returned by said tension spring, an abrading element rotatably mounted on said lighter body and in driving engagement with said extinguishing cap to be driven thereby, a spark producing member suitably supported on said lighter body to be acted upon by said abrading element, and a wick supplied with fuel from said fuel chamber and arranged on said lighter body within range of said spark producing element and adapted to be extinguished by said extinguishing cap, the recess in the staff-like lighter body serving as a catch for said yieldable extension to arrest said actuating member in its lower-most position, which is the position in which the extinguishing cap is fully opened.

4. The combination of a friction lighter and a pocket clip writing implement comprising a staff-like writing implement and lighter body having a fuel chamber therein, an actuating member in the form of a rod and comprising a projection thereon, said actuating member having the pocket clip at one end thereof integral with the rod and cooperating with the body and being shiftably mounted longitudinally of and on the outside of and along said lighter body to be moved by said projection, an extinguishing cap pivotally mounted on said lighter body and pivotally connected to the other end of said rod to be actuated thereby, an abrading element rotatably mounted on said lighter body and in driving engagement with said extinguishing cap to be driven thereby, a spark producing member supported on said lighter body to be acted upon by said abrading element, and a wick supplied with fuel from said fuel chamber and arranged on said lighter body within range of the sparks of said spark producing element and adapted to be extinguished by said extinguishing cap when the rod shifts longitudinally on the lighter body.

5. The combination of a friction lighter and a pocket clip writing implement comprising a staff-like writing implement and lighter body having

a fuel chamber therein, an actuating member comprising manual operating means, said actuating member having the pocket clip at one end thereof cooperating with the body and being shiftably mounted longitudinally of and on the outside of and along said lighter body, said lighter body having a longitudinal recess thereon, a tension spring mounted in said recess, said recess and tension spring being covered and concealed by said actuating member, said tension spring adapted to return said actuating member to its starting position at the end of each actuation, an extinguishing cap pivotally mounted on said lighter body and pivotally connected to the other

end of said actuating member to be actuated thereby and to be returned by said tension spring, an abrading element rotatably mounted on said lighter body and in driving engagement with said extinguishing cap to be driven thereby, a spark producing member supported on said lighter body to be acted upon by said abrading element, and a wick supplied with fuel from said fuel chamber and arranged on said lighter body within range of the sparks of said spark producing element and adapted to be extinguished by said extinguishing cap.

JOSEF EDENBURG.
